Patented Dec. 5, 1922.

INVENTOR.
MARTIN PARKER.

BY HIS ATTORNEY.
James F. Williamson

UNITED STATES PATENT OFFICE.

MARTIN PARKER, OF ST. PAUL, MINNESOTA, ASSIGNOR TO JOHN J. AHERN, OF ST. PAUL, MINNESOTA.

WRENCH.

Application filed December 10, 1920. Serial No. 429,685.

To all whom it may concern:

Be it known that I, MARTIN PARKER, a subject of the Dominion of Canada, residing at St. Paul, in the county of Ramsey and 5 State of Minnesota, have invented certain new and useful Improvements in Wrenches; and I do hereby declare the following to be a full, clear, and exact description of the invention, such as will enable others skilled in 10 the art to which it appertains to make and use the same.

This invention relates to a wrench and particularly to an adjustable wrench adapted to be used in place of a plurality of socket 15 wrenches.

It is an object of this invention to provide a wrench of extremely simple structure and which can be readily adjusted to fit various sized nuts.

20 It is a further object of this invention to provide a wrench of great strength which can be conveniently used instead of the ordinary socket wrench and which engages the nut from the top.

25 These and other objects and advantages of the invention will be apparent from the following description made in connection with the accompanying drawings in which like reference characters refer to the same parts 30 throughout the different views and in which:

Fig. 1 is a longitudinal central section of the device some of the parts of which are shown in elevation;

Fig. 2 is a partial plan view of the device; 35 Fig. 3 is a partial view similar to Fig. 1 showing the wrench expanded and engaging a nut.

Fig. 4 is a transverse sectional view on line 4—4 of Fig. 1;

40 Fig. 5 is a sectional view on line 5—5 of Fig. 1; and

Fig. 6 is a partial view showing a modified construction of the jaws on the wrench.

Referring to the drawings:

45 The device is seen to comprise a hollow tubular and tapered body portion having a tapered opening extending longitudinally therethrough and formed at one end into a square cross-section as shown in Fig. 5, to 50 provide a handle-receiving portion. A handle comprising two oppositely extending portions 2 and a central hub portion 3 is shown as having the hub portion formed with a square aperture to fit over the square end 55 portion of the body member. This handle

portion is therefore readily detachable when it is desired to carry the wrench in a tool kit or package. One side of the body portion is extended to form a stationary jaw member 4 and a hook portion 5 is formed on the 60 opposite side of the body portion over which is placed the movable jaw member 6, the same being provided near one end with a suitable aperture for engagement over the said hook.

65 Link members 7 are pivoted to the jaws near the ends thereof by suitable screws or rivets and these links are provided at each side of the jaws. The inner ends of the links 7 are connected together and also connected to the headed end of a rod 8 by suitable pivoted members 9. The rod 8 extends through the member 1 and projects from the other end thereof, this rod being threaded adjacent its projecting end to receive an adjusting nut 10. A suitable washer is provided between the nut 10 and the end of the body 1. The jaws are shown as provided with teeth or corrugations for more firmly 70 engaging a nut.

75 The wrench is designed primarily to be used in place of an ordinary socket wrench and to engage the nut from the end thereof although where it is convenient the nut may also be readily engaged from the side. To 80 adjust the jaw members the nut 10 is turned and the screw rod 8 moved longitudinally of the device. The link members 7 are then either opened or closed to move the jaws apart or towards each other. Since the 85 lower jaw as shown in Fig. 1 is stationary, the head end of rod 8 will swing on the lower links 7 about the fulcrum of the pivot at the end of said links and the end of rod 8 will therefore be raised when the jaws are in 90 open position and will approximately contact with the upper portion of the jaw member 1 as shown in Fig. 3. The upper jaws 6 will obviously swing about the hook member 5 as a fulcrum when the distance between the jaws is adjusted.

95 In Fig. 6 a modification is shown in which both the jaws 4' and 6' are similar and are pivoted at their inner ends to lugs formed on the end of the body member 1'. In this 100 construction both jaws will swing when the circular rod 8' is moved longitudinally and it is unnecessary to have a large opening in the body member to accommodate the swinging movement of the rod 8'. The wrench in 110

other particulars is of the same construction as that shown in Fig. 1.

It is thus seen that the applicant has produced a wrench of simple and rugged construction and one which can be inserted into a comparatively small space to reach nuts upon which an ordinary wrench cannot be used. The wrench can therefore be used in place of a socket wrench and by suitable adjustment thereof can be made to take the place of a large number of different sized socket wrenches. It will, of course, be understood that various changes in the form and details of the device may be made without departing from the scope of the invention which, generally stated, consists in the matter shown and described and set forth in the appended claims.

What is claimed is:

- 20 1. A wrench comprising a tubular body portion one side of which is projected to form a fixed jaw, a movable jaw in alignment with said fixed jaw and pivoted at its one end to said body portion, links pivoted to said jaws, a rod connected to said links and extending through the said tubular portion and an operating member for moving said rod and links to adjust the distance between said jaws.
- 25 2. A wrench comprising fixed and movable jaws, a body portion integrally connected to the fixed jaw, toggle link mechanism for moving said jaws toward and from each other and operating means for said mechanism extending through said body portion.
- 30 3. A wrench comprising a tubular body portion, a handle detachably secured at one end thereof, a fixed jaw projecting from the other end thereof, a movable jaw pivoted to said body portion for movement toward and from said fixed jaw, toggle links at each side of said jaws and an operating rod connected to said links and extending through the said body portion.
- 35 4. A wrench comprising a tubular body

portion, two jaw members carried thereby, one of which is movable, a pair of toggle links connected to said jaws and an operating rod connected at one end to both of said links and extending through said body portion and being threaded at its other end and an operating nut engaging said rod to move the same longitudinally to adjust the distance between the said jaws.

5. A wrench comprising a tapered tubular body portion, a handle detachably secured thereto at one end and a fixed jaw projecting from the other end thereof, a hook member formed at the last mentioned end opposite to the fixed jaw, a movable jaw pivoted on said hook member, a toggle link mechanism connected to said jaws at each side thereof, a rod connected at one end to said toggle mechanism and having its other end threaded and extended through said body portion and an operating nut engaging said threaded end of the rod to move the same longitudinally.

6. The structure set forth in claim 4, and a handle fitted to the outer end of said tubular body portion and extending transversely normal thereto for turning said body.

7. A wrench comprising a long body portion having jaws at its lower end, a link pivotally connected to each of said jaws adjacent the end thereof, a rod secured to the inner ends of said links and extending longitudinally through said body portion, means for moving said rod longitudinally and holding the same in position to variously position said jaws, and means on said body portion for turning the same.

8. A wrench comprising an elongated body portion having jaws at its lower end, one of which is adapted to move relatively to the other, a toggle mechanism connected to said jaws adjacent their ends for varying the distance therebetween, and means for adjusting said toggle mechanism.

In testimony whereof I affix my signature.

MARTIN PARKER.
